Specification for Design.

Patented Sept. 8, 1914.

Application filed July 3, 1914. Serial No. 848,953. Term of patent 3½ years.

To all whom it may concern:

Be it known that I, BRYAN HERBERT SMITH, a citizen of the United States, and a resident of the borough of Brooklyn, county of Kings, New York city, New York, have invented a new, original, and ornamental Design for Cotton Pongee Shirtings, of which the following is a specification.

Reference is to be had to the accompanying drawing, which illustrates a sample of the fabric, showing the new design.

In the drawing *a* represents what is known as a satin stripe; *b* is a section of momie

weave, or crape weave; *c* is a stripe of colored satin weave; *d* momie, or crape weave; *e* is a colored satin stripe; *f* momie or crape weave; *g* colored satin stripe. Unless otherwise specified, the fabric sections, cords, etc., are light colored or white.

I claim:

The ornamental design for cotton pongee shirtings, as shown and described.

BRYAN HERBERT SMITH.
